UNITED STATES PATENT OFFICE.

GEOERGE BLOW, OF KNOXVILLE, TENNESSEE.

LIQUID-LIFTING APPARATUS.

Application filed June 11, 1925. Serial No. 36,512.

This invention relates to apparatus for lifting liquids and while capable of general use, is particularly adapted for lifting water, oil, or other liquids from wells, 5 shafts, reservoirs, bilges or the like.

The common method of lifting liquids, particularly from deep wells or shafts, is by a pump located in the well and operated by a rod or wire line from the surface. The 10 cylinder, piston, and valve are necessarily placed at the bottom of the well, while the driving mechanism, of various types, is located at the well head. The disadvantage of this method and apparatus is the necessity for frequent repairs to or replacement 15 of the working parts because of friction therebetween or clogging of the same by sand and the like. Since most of the parts are inaccessible by reason of their location, 20 repairs to or replacement of the same requires the expenditure of considerable time, with the consequent increased cost of maintenance and decreased efficiency of the apparatus.

The principal objects of the present invention are to provide liquid lifting apparatus which overcomes the defects and disadvantages inherent in known apparatus such as above referred to; which carries out 25 a method utilizing the principles of the air lift and the hydraulic jet; which produces a differential of pressure on the nozzle tip for the hydraulic jet by decreasing the density or weight of one of two normally balanced 30 columns of liquid by means of suitable columns of liquid by means of suitable medium such as air injected therein; which maintains a constant pressure on the nozzle by a driving column of liquid supplied 35 at the head thereof through the medium of a pressure tank; which discharges the liquid 40 freely into the pressure tank and enables lifted liquid to be conducted therefrom by overflowing of the tank; which maintains a constant pressure on the driving column of 45 liquid by discharging the lifted liquid into the pressure tank; which secures the required differential of pressure by injection of the air at the desired depth in the column of liquid lifted; and which insures control of 50 the differential of pressure by the volume of air injected or by the depth of submergence of the air pipe.

Broadly stated, this invention consists in 55 overcoming the static balance of two columns of liquid, hereinafter designated

the driving column and the discharging column by decreasing the weight or density of the discharging column, preferably through the medium of a suitable gas such as air injected into said column or a portion 60 thereof; producing a hydraulic jet directed upwardly through the discharging column, by the differential of pressure obtained on the jet nozzle tip when the columns of liquid are unbalanced; causing liquid to circulate 65 in the system by maintaining constant pressure on the head of the driving column, preferably through the medium of a bulk of liquid into which the discharging column overflows; and lifting liquid from 70 a well or the like with the hydraulic jet and the discharging column.

This invention may be embodied in a variety of mechanical expressions, one of which is shown in the accompanying drawings, but it is to be expressly understood that the drawings are for purposes of illustration only and do not define the limits of the invention, reference being had to the appended claims for this purpose. 80

In said drawings,

Fig. 1 is a longitudinal section through apparatus embodying the invention and shown installed in a well or other reservoir of liquid to be lifted; 85

Fig. 2 is a side elevation of a foot nozzle or ejector adapted to be submerged within the well;

Fig. 3 is a vertical section on the line 3, 3 of Fig. 2; 90

Figs. 4, 5, 6 and 7 are horizontal sections on the lines 4—4, 5—5, 6—6, and 7—7, of Fig. 2;

Fig. 8 is an enlarged detail section of the pipe coupling shown in Fig. 1, illustrating 95 in detail a supplemental nozzle;

Fig. 9 is a horizontal section on the line 9—9 of Fig. 8;

Fig. 10 is a longitudinal central section through a pipe coupling provided with 100 another form of supplemental nozzle;

Fig. 11 is a horizontal section on the line 11—11 of Fig. 10; and

Fig. 12 is a vertical section on the line 12—12 of Fig. 11. 105

Referring to the drawings, wherein like characters designate like parts throughout the several views, 5 and 6 indicate two concentrically arranged liquid containers in the form of pipes which reach to or near the 110

bottom of a well 7 and terminate in a foot nozzle or ejector 8 submerged in the liquid of the well. The upper end of pipe 5 is secured in any suitable manner within an opening 9 formed in the bottom of a pressure tank 10 which constitutes in effect, an enlarged head for the pipe 5. Pipe 6 projects into tank 10 through opening 9 and has its upper open end disposed above the surface 10 of the liquid in said tank. An air pipe or hose 11 projects through the upper open end of pipe 6 and extends downwardly within the latter a distance less than the full length of pipe 6 and determined by the depth of the 15 well and the amount of liquid in the hole. Said air hose or pipe is connected with any suitable air pump or motor (not shown). When the apparatus is installed, the system is filled with any suitable driving fluid such 20 as water or oil. The nozzle 8 provides communication between pipes 5 and 6 and the two columns of liquid in said pipes are thus normally maintained in static balance.

Foot nozzle or ejector 8 preferably comprises a single casting having one movable part therein. As here shown, the casting provides concentrically arranged liquid containers in the form of an outer pipe 12, and an inner pipe 13 joined to said outer pipe 25 by hollow legs 14 which define ports 15 extending through the walls of the pipes adjacent the lower ends thereof. Pipes 12 and 13 are threaded or otherwise suitably secured on the lower ends of pipes 5 and 6 and legs 14 serve to conduct liquid from pipes 5 and 30 12 into the nozzle. The nozzle proper comprises the inturned upwardly directed end 16 of pipe 13 and the bottom closure 17 of pipe 12, the pipe end 16 and bottom closure 35 17 having opposed surfaces suitably curved to direct liquid descending downwardly through legs 14 upwardly through the nozzle and pipe 13. The inturned pipe end 16 is provided adjacent its base with a plurality 40 of pressure ports 18, and a seat 19 of rubber or other suitable material for a sleeve valve 45 20 which is slidably mounted in pipe 13 and normally rests on seat 19 as indicated by dotted lines in Figs. 1 and 3. When seated, said valve closes port 15 and prevents liquid 50 in well 7 from entering pipe 13.

Sleeve valve 20 is provided with a converging, diverging bore 19', which serves as a throat for the hydraulic jet produced by the 55 foot nozzle. The valve has a comparatively loose fit within pipe 13 so that it may fall by its own weight to close ports 15. Pipe 13 is provided intermediate its ends with flanges 21 and 22 and valve 20 is provided 60 intermediate its ends with an annular flange 23 which during movement of the valve has sliding contact with the annular space defined by flanges 21 and 22. The upper and lower surfaces of flanges 21 and 22 are preferably provided with seats 24 and 25 for

flange 23 and said seats may be of rubber or any other suitable cushioning material. Above flange 22, the pipe 13 is provided with a plurality of ports 26 through which liquid of the driving column in pipes 5 and 12 may be directed upwardly within pipe 13 against the lower surface of a comparatively wide annular flange 27 at the top of the sleeve valve, the driving fluid admitted between flanges 22 and 27 together with fluid admitted or directed through pressure ports 18, serving to lift valve 20. Flange 27 is preferably provided with a piston ring 28 but the provision of packing between said flange and pipe 13 is not essential since any leakage 70 at this point would not interfere with the operation of the apparatus.

Supplemental nozzles are preferably provided by a plurality of inclined ports 29 formed in pipe couplings 30 for the sections 85 of pipe 6 and said nozzles serve to direct small streams of liquid from pipe 5 upwardly into pipe 6 (Figs. 1, 8 and 9). The supplemental jets may also be produced by the construction shown in Figs. 10, 11 and 90 12 wherein the coupling 31 for adjacent sections of pipe 6' is provided with a substantially flat nozzle having a wide hollow base 32 extending across pipe 6' and terminating in ports, 33, 33, through which the liquid is 95 admitted from pipe 5'. The liquid after being admitted within the hollow base 32 is directed in a relatively small stream or jet upwardly into pipe 6' by the side and end walls 34 and 35 which for this purpose converge upwardly to provide a port 36 located 100 axially with respect to pipe 6' and through which the liquid is ejected therein.

During operation of the apparatus, a suitable gas such as air is forced through pipe 11 and discharges from the lower end thereof into the liquid contained in pipe 6. This decreases the density or weight of column C which is now composed of air and liquid. Column B is composed of liquid alone. Column A is also composed of liquid alone and is under a constant head of pressure from tank 10. Therefore the unit pressure of column B, C, at the nozzle, is less than driving column A. A jet of water will 115 therefore flow from the nozzle upwardly through the throat 19' of valve 20 and into the discharge conduit provided by pipe 6. There will thus be a constant circulation in the system as long as air is discharged 120 from pipe 11. It will be noted that the operation is in part an air lift, with the difference that the high percentage of submergence required by that method is not necessary with the present method. The difference in pressure at the nozzle may be regulated by the amount of air injected into discharging column B, C or by the depth of submersion of the air pipe or hose 11. It is to be particularly noted that the action 125 130 135

of the air injected in discharging column B, C is not that of forcing water out of the discharge pipe. The air simply changes the density or weight of the discharging column or a portion thereof and consequently produces the aforesaid differential of pressure on the nozzle tip by the unbalancing of driving column A and discharging column B, C. When the hydraulic jet has been produced in the manner stated, the higher pressure of column A acts to direct liquid through ports 26 against the annular flange 27 of sleeve valve 20. The high pressure driving column A also acts to direct liquid through pressure ports 18 against the base of the sleeve valve, and the combined effect of these pressures on the sleeve valve, assisted by friction of the jet through throat 19' of valve 20 lifts the valve to its upper position as shown in Figs. 1, 2 and 3. Ports 15 are thus opened and oil or other liquid in the well 7 is admitted into pipe 13 adjacent the nozzle. The hydraulic jet produced by the nozzle and throat 19' has the property of creating a suction behind it and carrying along any fluid entrained by this suction. Liquid from the well therefore flows to the hydraulic jet and is lifted with the discharging column B, C. Column B, C overflows at the upper end of pipe 6 into tank 10. A certain proportion of liquid overflows from tank 10 into an inclined trough 37 which leads to a storage tank 38 preferably disposed at a level lower than that of the pressure tank 10. The liquid flowing from pipe 6 into tank 10 serves to maintain the head of pressure on column A constant. The liquid overflowing from tank 10 constitutes the liquid lifted from the well, while the balance of the liquid lifted is retained within the system as circulating liquid. When columns A and B are unbalanced in the manner stated, the driving column will produce supplemental jets through the supplemental nozzles and these supplemental jets assist the lifting of column B, C and constitute what might be termed "booster" jets. Any desired number of supplemental nozzles may be employed and they may be placed at suitable intervals in the length of the pipe for column B, C. The total pressure on the booster nozzles will vary with depth but the differential of pressure under which they act will be the same for every point below the air discharge.

When it is desired to stop the lifting operation, the supply of air to the discharging column B, C is cut off. The jet will then flow until a static balance between columns A and B, C is obtained, at which time there is no differential of pressure to hold up the sliding sleeve valve 20. The valve therefore falls by its own weight onto seat 19, thereby closing ports 15 and preventing oil or liquid in the well from entering pipe 13. Closing

of the valve not only prevents liquid in the well from entering pipe 13 but also serves to retain driving liquid within the system and prevent discharge of the same into the well when the apparatus is not in operation. 70

It will thus appear that I have provided liquid lifting apparatus simple in its construction and operation, entirely automatic, and producing a continuous non-pulsating flow which can easily be regulated by varying the amount of air supplied or the depth of submergence of the air pipe. The present apparatus is capable of handling sand, slimes and other solids which are destructive to known equipment for pumping or lifting liquid. If a number of wells are to be "lifted" as on an oil lease, a central power plant may supply air through lines to apparatus installed in each of the wells. Moreover, lifting of liquid from all of the wells may be controlled from the same point by suitable valves on the line to each well. In this way, superintendence and maintenance may be concentrated and reduced to a minimum. It is to be expressly understood that the driving liquid may be oil, or water, or both, and that the apparatus is capable of lifting liquids other than oil and water. Moreover, the air or other suitable density reducing medium may be injected into the discharging column through various types of orifices, and nozzles other than the one particularly disclosed herein may be employed for producing the hydraulic jet. It is to be further understood that other methods and devices may be used to decrease the density of one of the two normally balanced columns of liquid without departing from the spirit of this invention. These and other changes in the procedure and the form and construction of the apparatus are therefore intended within the limits of the appended claims. 100 105 110 115 120 125 130

What is claimed is:—

1. In a liquid lifting apparatus, the combination of communicating containers for two normally balanced columns of liquid, a device for aerating one liquid column to reduce its density, a nozzle for producing a hydraulic jet in the aerated column by the driving effect of the other column, and a valve in the path of said jet and actuated thereby to automatically establish communication between the container for the aerated column and a well or the like, whereby liquid in the latter flows to the hydraulic jet and is lifted with the aerated column. 110 115 120

2. In a liquid lifting apparatus, the combination of communicating containers having two normally balanced columns of liquid therein, means for unbalancing said columns and causing the liquid in one container to discharge into the other container, said means comprising a device for aerating one column and a nozzle producing a hydraulic jet in the aerated column by the 125 130

driving effect of the other column, and means acted upon by said jet and controlling communication between the container for the aerated column and a well or the like, whereby liquid in the latter flows to the hydraulic jet and is lifted with the discharging aerated column.

3. In combination, two containers disposed one within the other adapted to be placed in a well or the like and terminating in a nozzle directed upwardly within the inner container, a valve in the inner container controlling communication between the latter and the well, and means for directing fluid under pressure against said valve to lift the same and admit liquid from the well into the inner pipe adjacent said nozzle.

4. In combination, two containers disposed one within the other adapted to be positioned in a well or the like, a nozzle directed upwardly within the inner pipe, and a valve for controlling the passage of fluid from the well into the inner pipe, said valve having a throat receiving the jet from said nozzle.

5. In combination, two liquid containers disposed one within the other adapted to be positioned in a well or the like, a nozzle on the outer container directed upwardly within the inner container, and a valve slidably mounted within the inner container and having a converging-diverging bore providing a throat for receiving the jet of said nozzle, said valve controlling the passage of fluid from the well into the inner pipe.

6. In combination an inner and an outer conduit having an inlet port and terminating in a nozzle directed upwardly within the inner conduit, a valve for admitting fluid through said port between the inner conduit and the nozzle, and means for directing fluid under pressure from the outer conduit

against said valve to lift the same and open said port.

7. In combination an inner and an outer liquid container having an inlet port in the walls thereof, said containers terminating in a nozzle directed upwardly within the inner container, a valve in the inner container normally closing said port and normally seated over said nozzle, and means for directing liquid under pressure against said valve to lift the same and open the port.

8. In combination an outer and an inner conduit terminating in a nozzle directed upwardly within the inner conduit, said conduits having one or more ports in the walls thereof, a valve in said member normally closing the port or ports and having a throat for the jet from the nozzle, and means for directing liquid under pressure from the outer conduit against said valve to lift the same and open the port or ports.

9. In combination an outer and an inner conduit terminating in a nozzle directed upwardly within the inner conduit, said member having one or more ports in the walls thereof for admitting liquid between the inner conduit and the nozzle, a valve normally seated over the nozzle to close the ports and having a throat for the jet of the nozzle, and means for lifting the valve by fluid pressure from the outer conduit.

10. In combination, two containers disposed one within the other and adapted to be placed in a well or the like, a nozzle directed upwardly from the outer into the inner of said containers, an opening from said well to said inner container, and a pressure actuated valve normally closing said opening, and operable by a jet from said nozzle impinging thereon.

In testimony whereof I have signed this specification.

GEORGE BLOW.
